UNITED STATES PATENT OFFICE.

ARMAND H. PEYCKE, OF CHICAGO, ILLINOIS, ASSIGNOR TO AMERICAN STEEL
FOUNDRIES, OF CHICAGO, ILLINOIS, A CORPORATION OF NEW JERSEY.

RELEASING MEANS AND LEVELING DEVICE.

1,315,398.

Specification of Letters Patent. Patented Sept. 9, 1919.

Application filed February 13, 1918. Serial No. 217,006.

To all whom it may concern:

Be it known that I, ARMAND H. PEYCKE, a citizen of the United States, and resident of Chicago, in the county of Cook and State of Illinois, have invented certain new and useful Improvements in Releasing Means and Leveling Devices, of which the following is a specification.

This invention relates to brake releasing and leveling device means.

One of the objects of the invention is to eliminate a relatively large number of parts for performing the functions of releasing the brakes and leveling the same.

Another object is to provide release and leveling device means which may be applied to a railway car truck in various places therefor without alteration thereof.

Generally speaking, these and other objects are accomplished by providing, in a railway car truck, means interposed between a plurality of brake beams for giving the same a yieldable releasing movement.

The invention is illustrated on the accompanying sheets of drawings, in which—

Figure 1 is a fragmentary plan view of a railway car truck embodying my invention;

Fig. 2 is a fragmentary side elevation of the same showing end and intermediate car truck portions superimposed upon each other to point out the advantages of my invention;

Fig. 3 is a sectional view taken on the plane of line 3—3 of Fig. 2; and

Figs. 4 to 9, inclusive, are detail sectional views showing various modifications of means for operatively connecting the releasing spring and the brake beam.

The various novel features of my invention will be apparent from the following description and drawings and will be particularly pointed out in the appended claims.

With the ordinary six-wheel truck, twenty-four releasing springs per car heretofore have been used. Also in this connection with this old method there were three different shapes of releasing springs, and sometimes four. This was due to the method of fastening the releasing springs to the truck, certain parts of which are arranged differently with respect to the associated wheels.

Reference being had particularly to Fig. 2 of the drawings, it will be noted that I have shown the end portion of a railway car truck frame and indicated the outline of the same

by the reference character 10. In the same figure I have also shown superimposed upon the end portion of the truck frame, an intermediate portion of the truck frame, the outline of which is indicated by the reference character 11. From this figure it is apparent that where a separate releasing spring was used for each end of each beam, it was quite natural that releasing springs of three or four designs were used in connection with a single truck. To avoid the use of a multiplicity of designs of releasing springs and to greatly reduce the necessary number of releasing springs, I have chosen to provide a single releasing spring to be used in common with two associated brake beams at each end thereof, said brake beams being arranged upon opposite sides of a given pair of wheels.

The brake beams 12 in this case are part of a clasp brake rigging, being shown upon opposite sides of a pair of wheels 13, one only of which is shown. Taking advantage of the fact that the height of the different portions of the truck frame over the center of the car wheel axle is the same, I have anchored a single releasing spring, or resilient member 14 to the car truck directly over the axle of the car wheels, this spring 14 preferably being secured to the wheel guard of the car frame. Any pair of wheels and axles can be dropped from the truck without removing springs or beams. This single spring, which extends between the beams, in each case has its ends connected to each of the associated brake beams 12 preferably near the ends thereof, it being understood, of course, that preferably there is a spring 14 at each side of the truck for each pair of wheels. This releasing spring 14 has a single central loop, which is the part secured to the wheel guard, and has adjacent the brake beams 12 two loops whereby the ends of the spring extend upwardly toward the brake beams, overlap the latter, and are secured thereto by a bolt and nut arrangement 15. This releasing spring 14, which is located intermediate the associated brake beams, not only serves the function for giving the brake beams a releasing movement when the brakes are released, but also performs the function of a leveling device to maintain the brake shoes in concentricity with the tread of the associated wheels 13. The sole purpose of fastening

the releasing spring 14 to the frame at the point 16, which is the middle point of the spring, is to prevent longitudinal shifting movement of the spring 14 and to make possible the equalization of the releasing action. The wheel guard is chosen as the anchoring support for the releasing spring because it is the handiest place and because its position relative to the wheel axles in each case is constant. These springs are interchangeable, thereby making it possible for any one of the same to be transferred from one set of brake beams to another without any alterations being made.

In Fig. 5 of the drawings I have shown the releasing and leveling spring 14 as having a wedge portion 17 which is drawn toward the web of the I-shaped brake beam 12 and secured to the beam by a bolt and nut arrangement 18. It will be appreciated that the tighter the nut is drawn the greater will be the clamping action between the end of the spring 17 and the beam 12.

In Fig. 6 I have shown the end of the spring 14 secured to the beam 12 by hooking the end of the spring over one portion of the flange of the beam and pressing a clip into engagement with another portion of the flange by means of a bolt and nut arrangement 19, which secures the clip to the end of the spring 14.

In Fig. 9 the end of the spring is bent over into engagement with the web of the beam 12 and secured thereto by a rivet 20. In all of the arrangements thus far described, it will be noted that the spring 14 is directly secured to the brake beam, in which case the spring not only serves as a releasing means, but also as a leveling means.

By referring to Figs. 4, 7 and 8, it will be noted that in each case I have provided the brake beam 12 with a clip 21, the sole function of which is to prevent wear as the result of a sliding movement of the end of the spring 14 with respect to the beam. In Fig. 4 the end of the spring is slightly curved to slidably engage the clip 21. In Fig. 7 the end of the spring 14 is bent to pass over and embrace the beam 12, while in Fig. 8 the end of the spring 14 is looped below the beam 12 in an embracing manner. In the modifications shown in Figs. 4, 7 and 8, the spring 14 serves only as a releasing spring. It is preferable, of course, to secure the springs to the beams, thereby eliminating the necessity for the spring clips.

By means of my releasing and leveling device arrangement, many parts are eliminated and but a single design is necessary to meet in an improved manner the various requirements for successful commercial operation. If desired, instead of providing a single spring, two or more duplicate springs may be provided. The ends of the two springs may meet at a common anchor-

ing point or not, as desired. However, the springs should be secured to the wheel guard and be located for the most part between the associated beams.

It is my intention to cover all modifications falling within the spirit and scope of the following claims.

What I claim is:

1. In a railway car truck, the combination of brake beams on opposite sides of a pair of wheels, and a member anchored intermediate its ends and extending between said brake beams for giving the latter a releasing movement when the brakes are released. 75

2. In a railway car truck, the combination of brake beams on opposite sides of a pair of wheels, and a resilient member anchored intermediate its ends and extending between said brake beams for giving the latter a releasing movement when the brakes are released. 80

3. In a railway car truck, the combination of brake beams on opposite sides of a pair of wheels, and a single spring extending between and engaging said brake beams for giving the latter a releasing movement when the brakes are released. 85

4. In a railway car truck, the combination of associated brake beams, and a single anchored member located between said brake beams for giving the latter a releasing movement when the brakes are released. 90

5. In a railway car truck, the combination of a brake beam, and means secured to the wheel guard of the truck directly above an axle for giving the beam a releasing movement when the brake is released. 100

6. In a railway car truck, the combination of brake beams on opposite sides of a pair of wheels, means extending between said brake beams for giving the latter a releasing movement when the brakes are released, and means for supporting an intermediate portion of said means. 105

7. In a railway car truck, the combination of associated brake beams, a single member extending between said beams for giving the latter a releasing movement when the brakes are released, and means for proportioning the releasing action of said means on said beams. 110

8. In a railway car truck, the combination of brake beams on opposite sides of a pair of wheels, and a single spring extending between said beams for giving the latter a releasing movement when the brakes are released, an intermediate point of said spring being anchored to proportion the releasing action of said spring on said brake beams. 120

9. In a railway car truck having two or more wheels, brake beams on opposite sides of each pair of wheels, and a releasing spring operatively connected to and between a set of brake beams on opposite sides of a pair of wheels for giving the brake beams a re- 125

130

leasing movement when the brakes are released, the releasing springs for all of said pairs of wheels being interchangeable.

10. In a railway car truck, the combination of brake beams on opposite sides of a pair of wheels, and a spring extending between and secured to said beams for giving the latter a releasing movement when the brakes are released and for leveling said

10 beams.

11. In a railway car truck, the combination of brake beams on opposite sides of a pair of wheels, and single continuous means extending between and secured to said beams

15 for giving the beams a releasing movement when the brakes are released and for leveling said beams.

12. In a railway car truck, the combination of associated brake beams on opposite sides of a pair of wheels, and single continuous means extending between and secured to said brake beams for leveling the latter. 20

13. In a railway car truck, the combination of associated brake beams on opposite sides of a pair of wheels, and a single spring 25 extending between and secured to said brake beams for leveling the latter.

Signed at Chicago, Illinois, this 26th day of January, A. D. 1918.

ARMAND H. PEYCKE.
